UNITED STATES PATENT OFFICE.

LEONARD AITKEN, OF LAWRENCE, MASSACHUSETTS, ASSIGNEE TO LAWRENCE DUCK COMPANY, OF LAWRENCE, MASSACHUSETTS, A CORPORATION OF MASSACHUSETTS.

AUTOMATIC WEFT-REPLENISHING LOOM.

1,375,885.

Specification of Letters Patent. Patented Apr. 26, 1921.

Application filed September 9, 1915, Serial No. 49,763. Renewed June 9, 1919. Serial No. 303,001.

To all whom it may concern:

Be it known that I, LEONARD AITKEN, a citizen of the United States, and resident of Lawrence, in the county of Essex and State 5 of Massachusetts, have invented certain new and useful Improvements in Automatic Weft-Replenishing Looms, of which the following is a specification.

This invention relates to looms that have 10 means for automatically replenishing the filling. My copending application, Serial No. 831,355, filed April 13, 1914, shows such a loom, and the present invention consists in improvements applicable to such a loom.

15 Of the accompanying drawings:

Figure 1 represents an end elevation of the change end of a loom embodying the improvements hereinafter described.

Fig. 2 represents an elevation, partly 20 broken out, of shuttle-ejecting mechanism which is shown in part in Fig. 1.

Fig. 3 represents a vertical section, on a larger scale, in a plane from front to rear of the loom, through the shuttle-changing 25 mechanism.

Fig. 4 represents a sectional view showing the shuttle box portion of the lay and the upper portion of the shuttle carrier, the latter being about to deposit a filled shuttle 30 in the shuttle box.

Fig. 5 represents a sectional view showing the shuttle carrier as having deposited a filled shuttle in the shuttle box and as having not returned from the shuttle-depositing 35 position. The spent shuttle is about to be deposited upon the shuttle carrier.

Fig. 6 represents an elevation of the shuttle carrier in the same position as that shown by Fig. 5, with the spent shuttle deposited 40 thereon.

Fig. 7 represents a top plan view of the change end or shuttle-box portion of the lay, the rear of the lay being toward the top of the figure.

45 Fig. 8 represents a top plan view of the shuttle carrier, with a filled shuttle, represented by dotted lines, resting thereon.

Fig. 9 represents a vertical section, on a still larger scale, through the shuttle carrier, in a plane indicated by line 9-9 of Fig. 8.

The same reference characters indicate the same parts wherever they occur.

Inasmuch as the improvements which 50 constitute the present invention relate exclu-

sively to the shuttle-changing mechanism, a brief description of the loom will be sufficient for present purposes.

The loom uses two shuttles alternately. While one shuttle is traveling back and forth 60 through the shed, the other shuttle is held in reserve; and when the filling in the working shuttle is about to run out, the weaving mechanism is automatically stopped through the action of well known feeler mechanism. 65 The stopping of the weaving mechanism is followed by the operation of the shuttle-changing mechanism, whereby the spent shuttle is taken away from the shuttle box of the lay, and the reserve shuttle, containing 70 a filled bobbin, is substituted for the spent shuttle. The interchange of shuttles is followed by the transfer of the spent shuttle to loading mechanism which includes a bobbin magazine and means for transferring 75 a filled bobbin from said magazine into the spent shuttle. The weaving mechanism is automatically set in operation after the shuttles have been interchanged, and may continue in operation until another weft- 80 replenishing operation is necessary.

The working shuttle and the reserve shuttle are indicated respectively at α and α' in Fig. 1. The reserve shuttle rests upon a support 10. The shuttle box at the change end 85 of the lay 11 includes the usual binder 12, the usual overhanging shuttle-guard 12* and the movable shuttle-box front 13. Suitable clutch mechanism (not shown) which is commonly used in weft-replenishing looms 90 known as the "Stafford" loom, is controlled by feeler mechanism to stop the weaving mechanism and to operate the replenishing mechanism whenever new filling is required. In order to permit the interchange of shuttles, the movable shuttle-box front 13 is raised above the top of the shuttle, as shown by Figs. 3 and 5. The member 13 is carried by arms 14 which are pivotally mounted upon a rod 15. This rod is mounted in a 100 bracket 16 carried by the lay. An arm 17 rigidly connected to the arms 14 is connected by a link 18 with a cam lever 19. The fulcrum member of this lever is indicated at 20. A roll 21 carried by the lever 105 is arranged to be engaged by a cam 22. This cam is affixed to a shaft 23, which shaft is sometimes termed the change shaft in the Stafford loom hereinbefore mentioned. The cam raises the shuttle-box front and holds 110

the latter elevated for a sufficient length of time to permit the removal of the spent shuttle and the deposit of the reserve shuttle, and the return movement of the shuttle-box 5 front is caused by a tension spring 24.

The automatic stop mechanism is timed to cause the lay to stop at or near the position shown by Figs. 1, 3 and 5. As soon as the shuttle-box front 13 has been raised 10 sufficiently to release the spent shuttle, the latter is ejected by ejecting mechanism which is shown by Fig. 2. The ejector or shuttle-engaging member is indicated at 25. It is affixed to an arm 26 which is mounted 15 upon a pivot pin 27 arranged below and movable with the lay. The ejector is arranged to extend between the shuttle-binder 12 and the guard 12^x that overhangs the latter, and is curved so as to be substantially 20 concentric in relation to the axis about which it swings when ejecting a shuttle. A stud or projection 28 carried by the arm is bored for the reception of a rod 29. The lower end of this rod is pivotally connected 25 to a lever 30. This lever is arranged upon the fulcrum member 20 hereinbefore mentioned, and is provided with a projection 31 which is arranged to coact with a cam 32 on the shaft 23. The effect of the cam is to 30 raise the rod 29, and such movement of the rod is transmitted to the arm 26 by a helical compression spring 33. This spring is arranged upon the rod and compressed between the stud 28 and a collar 34, the latter being fastened to the rod. The spring 33 35 enables the ejector to stop in case the shuttle should become caught, and permits the rod 29 to have its full upward movement without causing breakage or injury of the 40 connections. Furthermore, the spring has a cushioning effect which lessens the force of the impact of the ejector against the shuttle. It will be observed that the point of initial contact between the ejector and the shuttle 45 is a substantial distance above the center of the shuttle. In the Stafford loom hereinbefore mentioned, the ejector is arranged to engage the shuttle initially near the bottom or below the center of the latter, such relation being due to the fact that in the stafford loom the pivot about which the ejector swings is above the shuttle. One objection to the ejector in the Stafford loom is that it sometimes causes the shuttle to tip over and 50 lie upon its side. This is due primarily to the fact that the shuttle-supporting surface of the lay is inclined considerably with relation to a horizontal plane when the shuttle-changing operation takes place. At such time the top of the shuttle is tipped toward the rear of the loom, and the shuttle consequently tends to tip over upon its rear side. This tendency is increased by the Stafford 55 ejector, because the latter strikes the shuttle below the center. The tipping of the shuttle

in the Stafford loom is not especially objectionable, because the shuttle is not reloaded automatically but is merely discharged from the loom upon the floor or into a receptacle lying upon the floor. But in a loom which 70 has mechanism for automatically reloading the spent shuttle, it is necessary to keep the shuttle always in coöperative relation to the devices which act upon it. It is for this reason that I have arranged the ejector, in the 75 present instance, to engage the shuttle initially above the center, in which relation the initial tendency of the shuttle to tip back, due to the inclination of the shuttle-supporting surface of the lay, is neutralized. 80 It is not necessary that the point of contact between the ejector and the shuttle remain above the center of the shuttle throughout the ejecting movement; for when the inertia of the shuttle has been overcome, the 85 tendency to tip over will not be sufficient to cause actual tipping. Fig. 2 includes dotted lines indicating the extent to which the ejector moves. From this it may be seen that the point of engagement between the ejector 90 and the shuttle will progress downwardly with relation to the shuttle, and that said point will be approximately midway between the top and bottom of the shuttle when the ejector has reached the limit of its 95 ejecting movement.

As the shuttle is ejected it passes from the lay to a receiver 35. A plan view of the receiver is included in Fig. 7. It has flange portions 36, 36 which are arranged to be 100 engaged by the front side of the shuttle to prevent over-travel of the shuttle. The end portions 37 of these flanges are curved to coöperate with the end portions of the shuttle so as to register the shuttle endwise with 105 relation to the device by which the shuttle is subsequently taken. The receiver has guiding flanges 38, 38 which are arranged to slide in guides 39, 39 carried by the lay. The receiver is affixed to the upper end of a 110 rod or post 40, the lower end of which is guided by a member 41 which oscillates with the sword shaft 42. A member 43 is affixed to the rod 40 and is arranged to coact with a cam lever 44. The fulcrum of this lever 115 is the member 20 hereinbefore mentioned. A boss 45 formed upon the lever rests upon a cam 46, said cam being carried by the shaft 23. The effect of the cam is to lift the receiver 35, to elevate the spent shuttle as 120 shown by Fig. 5 and as indicated by dotted lines in Fig. 3. The spent shuttle is held in its elevated position for a sufficient length of time to permit the shuttle carrier, herein-after described, to carry the reserve shuttle 125 into the shuttle box.

The shuttle carrier is indicated as a whole at 50, and it includes an arm or lever 51 and other details which will be described in due course. The arm 51 is arranged upon a sta- 130

tionary fulcrum stud 52 (Fig. 1), and it carries a cam roll 53 which coacts with a cam 54 on the shaft 23.

While the weaving mechanism is in operation the shuttle carrier remains stationary in the position shown by Fig. 1 and by full lines in Fig. 3; but in the course of changing the shuttles the carrier moves from the said position to the position shown by Fig. 5, thereby carrying the reserve shuttle from the support 10 to the shuttle box of the lay. This movement of the carrier is effected by a helical tension spring 55, and the return movement of the carrier is effected by the cam 54.

The main body of the shuttle carrier has a shuttle-supporting surface 56 upon which the spent shuttle rests while being carried to the support 10. The reserve shuttle, in traveling from the support 10 to the shuttle box of the lay, does not rest upon the surface 56 but rests upon a pair of fingers 57. The rear ends 58 of these fingers are bent upwardly so as to engage the rear side of the shuttle, as shown by Fig. 4 and by dotted lines in Fig. 3. The carrier is provided with a clamping device 60 by which the spent shuttle is held in place upon the surface 56. The clamping device is pivotally mounted upon the rod 61 which is affixed to the carrier. A helical torsion spring 62 is coiled about the rod, and one end thereof is hooked to the device 60 as shown best by Fig. 9. The other end 63 of the spring is arranged in a hole formed in a collar 64. This collar is mounted upon the rod and is fastened thereto by a setscrew 65. The collar is set in a position that will keep the device 60 constantly under spring stress and normally in contact with the body of the carrier as indicated at 66. The carrier is provided with a pair of upstanding ears 67 at its front side, in position to be engaged by the front side of the spent shuttle. The clamping device 60 has a pair of ears 68 whose surfaces 69 are arranged to engage the rear side of the spent shuttle. When the device 60 is in its normal position as shown by Fig. 9, the distance between the surface 69 and the confronting surfaces of the ears 67 is slightly less than the width of the shuttle, and in order to insert the shuttle between them it is necessary to depress the device 60 slightly against the stress of the spring 62. Consequently when the spent shuttle is seated upon the surface 56 it is clamped against the ears 67 by the ears 68 and is thus held with sufficient force to prevent displacement.

The clamping device 60 carries a pair of clamping devices 70, 70 which coact respectively with the upturned ends 58 of the shuttle-supporting fingers 57 to clamp the filled shuttle. The members 70 are connected to the ears 68 by pivot pins 71. Headed

studs 72 are affixed to the clamping device 60 and extend loosely through holes 73 in the members 70. Helical compression springs 74 are arranged upon the studs 72 and are compressed between the device 60 70 and the devices 70, and force the latter toward the ends 58 of the fingers 57. The heads 75 of the studs are arranged to keep the members 70 from being forced too far in the direction of the ends 58. When the members 70 are in their normal positions as shown by Fig. 9, the distance between them and the confronting faces of the ends 58 is slightly less than the width of the shuttle, and it is necessary to force the members 70 80 away from the ends 58 in order to permit the shuttle to rest upon the fingers 57 as shown by Fig. 4. But when the shuttle is seated upon the fingers as shown by Fig. 4, its rear side is clamped against the ends 58 85 by the stress of the two springs 74, and the shuttle is thus held firmly upon the carrier during its passage from the support 10 to the shuttle box of the lay.

Assuming that the weaving mechanism 90 has been stopped for replenishment of the weft and that the shuttle-changing mechanism has been set in operation as hereinbefore partly explained,—the carrier 50 moves from the position shown by Figs. 1 and 3 95 toward the lay. The shuttle-supporting fingers 57 pass under the shuttle α' resting on the support 10, and the clamping members 70 engage the front side of the shuttle, thereby moving the shuttle toward the lay. 100 The inertia of the shuttle is sufficient to move the members 70 against the stress of the springs 74, and although the springs react almost immediately, the interval is sufficient to enable the shuttle to take its place 105 in the angle of the fingers 57, 58.

In order to disengage the filled shuttle from the upturned ends 58 of the fingers 57 so that the fingers will not pull the filled shuttle out of the shuttle box after having 110 deposited it there, the fingers are arranged so that their tips traverse an arc lower than that traversed by the shuttle-supporting surface of the lay. (See Fig. 5). In this connection it is necessary to raise the filled 115 shuttle relatively to the fingers 57 in order to enable the filled shuttle to go into the shuttle box. For this reason the lay is provided with a pair of fingers 76 which project toward the front of the loom, as shown 120 by Figs. 4 and 7. The upper surfaces of these fingers are inclined relatively to the shuttle-supporting surface of the lay, and are arranged to intersect the arc traversed by the rear bottom edge of the shuttle. It 125 follows, therefore, that the shuttle will ride upon the fingers 76 and will thus be lifted out of engagement with the tips 58 of the fingers 57, and during the remainder of the movement of the carrier toward the lay the 130

filled shuttle will be supported by the lay although still receiving lateral movement from the carrier.

The carrier has an interval of dwell in the position shown by Fig. 5, during which the receiver 35 descends to deposit the spent shuttle α upon the surface 56. As hereinbefore stated, it is necessary to depress the clamping device 60 in order to seat the spent shuttle upon the surface 56. Such seating of the shuttle is insured by one or more shuttle-engaging portions 77 on the shuttle-box front 13. (See Fig. 5). When the receiver 35 descends, the lower front edge of the shuttle settles into the angle formed by the surface 56 and ears 67, but the lower rear edge of the shuttle is caught by the ears 68 of the clamping device. The cam 22 is timed to cause the shuttle-box front to descend during the carrier's interval of dwell in the position shown by Fig. 5, and during the descent of the shuttle-box front the portion or portions 77 engage the upper rear edge of the spent shuttle and bear downwardly thereon with sufficient force to depress the member 60 and seat the shuttle on the surface 56. As the member 13 continues to descend, it engages the ears 68 and further depresses the member 60 against the stress of the spring 62, but as soon as the ears 68 have been disengaged from the member 13 in consequence of return movement of the carrier, the member 60 rises in response to its spring 62 until its movement is arrested by clamping action on the shuttle.

Before the shuttle carrier reaches its extreme forward position the front side of the spent shuttle thereon engages the front wall 10' of the shuttle support 10, and the shuttle is thereby arrested. The clamping device 60, however, continues to move with the carrier and is deflected downwardly by the shuttle so that the ears 68 pass under the shuttle before the device is returned to its normal position as shown by Fig. 9.

After the spent shuttle has been deposited upon the support 10, but before the change shaft 23 has completed one revolution, a dagger 80 (Fig. 1) is raised so that its rear end will register with a striker 81 carried by the lay. The function of the members 80 and 81 is to operate the loader 82, which transfers a full bobbin from the magazine 83 to the shuttle α' . The forward end of the dagger 80 is connected by a pivot member 84 to an arm 85. This arm is arranged to swing upon a pivot rod 86, and it has suitable connection with the loader 82 which is likewise pivoted upon said rod. As shown by Fig. 1, the member 80 rests upon the upper end of a rod 87. This rod is carried by a member 88 whose lower end is connected by pivot member 89 with a cam lever 90. This lever has a toe 91 which rests upon a

cam 92 on the change shaft 23. The lever 65 90 is mounted upon the fulcrum member 20 hereinbefore mentioned. As the lever is raised by the action of the cam 92 the member 88 rises and such motion is transmitted to the rod 87 by a cushioning spring 93, the latter being adapted to observe the movement of the member 88 in case the striker 81 should overhang the free end of the dagger 80 so as to prematurely arrest upward movement of the latter. 75

The dagger 80 is provided with a pin or other projection 94 against which a latching device 95 bears. This latching device is mounted upon a pivot stud 96 and has a weight portion 97 by which the member 95 80 is automatically moved under the projection 94 when the latter has risen to its highest position. The dagger 80 is thus latched in register with the striker 81, although the rod 87 is permitted to descend immediately 85 by its lifting cam 92. The dagger 80 remains in register with the striker 81 until the lay has gone forward and part way to the rear after the interchange of shuttles. As the dagger 80 is carried forward by the 90 striker 81 it transmits the necessary motion to the arm 85 to cause the loader 82 to descend, and, at the same time, the projection 94 on the dagger is carried beyond the latching device 95 so that the dagger is no longer 95 supported by the latching device but is supported exclusively by its pivot member 84 and by the striker 81. As the striker moves to the rear after having caused the operation of the loader 82, it releases the rear 100 end of the dagger 80, and the latter then drops, the projection 94 at such time being in front of the latching device 95.

The stopping of the change shaft 23 and the restarting of the weaving mechanism is 105 caused automatically when the change shaft has completed one revolution. The mechanism for those purposes includes a starting shaft 100, an arm 101 affixed thereto, a rod 102 pivotally connected at 103 to the arm 110 101, a collar 104 affixed to said rod, an operating lever 105 mounted upon fulcrum member 20, and a starting cam (not shown) on the shaft 23. The elements just recited are all well known and operate in the well 115 known manner, and no further description of them will be necessary.

I claim:

1. In a weft-replenishing loom, the combination with a shuttle box having a shuttle-binder and an overhanging shuttle-guard, of a shuttle-engaging device mounted upon a pivot arranged under, and movable with, said shuttle-box, said device being arranged to extend between said shuttle-binder and said shuttle-guard to engage the rear side of the shuttle near the top, and means arranged to actuate said device when the

shuttle-box is inclined toward the rear of the loom, to move the shuttle toward the front of the loom.

2. In a weft-replenishing loom, the combination with the "change" shuttle-box, of means arranged to put a full bobbin in a spent shuttle, a shuttle-carrier and operating means therefor arranged to carry the filled shuttle from the first said means to said shuttle-box, said shuttle-carrier having means arranged to clamp the filled shuttle.

3. In a weft-replenishing loom, the combination with the "change" shuttle-box, of means arranged to put a full bobbin in a spent shuttle, a shuttle-carrier and operating means therefor arranged to carry the filled shuttle from the first said means to said shuttle-box, said carrier having means arranged to clamp the front and rear sides of the filled shuttle.

4. In a weft-replenishing loom, the combination with the "change" shuttle-box, of means arranged to put a filled bobbin in a spent shuttle, a shuttle-carrier and operating means therefor arranged to carry the filled shuttle from the first said means to said shuttle-box, an abutment on said carrier arranged to engage the filled shuttle, and a spring-pressed clamping device on said carrier arranged to coact with said abutment to clamp the filled shuttle.

5. In a weft-replenishing loom, the combination with the "change" shuttle-box, of means arranged to put a filled bobbin in a spent shuttle, a shuttle-carrier and operating means therefor arranged to carry the filled shuttle from the first said means to said shuttle-box, yielding cushioning means carried by said carrier and arranged to push the filled shuttle from the first said means to said carrier, and means on said carrier and arranged to coact with said cushioning means to clamp the shuttle.

6. In a weft-replenishing loom, the combination with the "change" shuttle-box, of means arranged to put a full bobbin in a spent shuttle, a shuttle-carrier and operating means therefor arranged to carry the filled shuttle from the first said means to said shuttle-box, means arranged to clamp the shuttle on said carrier, and means arranged to release the shuttle from said clamping means.

7. In a weft-replenishing loom, the combination with the "change" shuttle-box, of means arranged to put a full bobbin in a spent shuttle, a shuttle-carrier and operating means therefor arranged to carry the filled shuttle from the first said means to said shuttle-box, means arranged to clamp the shuttle on said carrier, and means carried by said shuttle-box and having a shuttle-deflecting surface arranged to release the shuttle from said clamping means.

8. In a weft-replenishing loom, the com-

bination with the "change" shuttle box, of means arranged to interchange a filled shuttle and a spent shuttle in said shuttle-box, bobbin-supplying means arranged to put a full bobbin into a spent shuttle, the first 70 said means being arranged to transfer the shuttles from said bobbin-supplying means to said shuttle-box and vice versa, said interchanging means including shuttle-clamping means arranged to hold the filled shuttle 75 and including shuttle-clamping means arranged to hold the spent shuttle.

9. In a weft-replenishing loom, the combination with the "change" shuttle-box, of a shuttle-support, means arranged to put 80 a full bobbin in a spent shuttle on said support, a shuttle-carrier, shuttle-clamping means carried by said carrier and arranged to receive a spent shuttle from above, said shuttle-clamping means including a spring- 85 pressed clamping element, means arranged to transfer a spent shuttle from said shuttle-box to said clamping means, means arranged to depress the spent shuttle into said shuttle-clamping means, means arranged to move 90 said carrier to transfer the spent shuttle to said shuttle-support, and means arranged to put a full bobbin into the spent shuttle on said shuttle support.

10. In a weft-replenishing loom, the combination with the "change" shuttle-box, of a shuttle-support, a shuttle-carrier having a platform for a spent shuttle and a platform for a filled shuttle, an abutment and a spring-pressed shuttle-engaging element arranged on said carrier to clamp a spent shuttle on said spent-shuttle-platform, a spring-pressed device and an abutment arranged to clamp a filled shuttle on said filled-shuttle-platform, means arranged to put a full bobbin in a spent shuttle on said shuttle-support, means arranged to move said carrier to carry the filled shuttle from said shuttle-support to said shuttle box, and means arranged to transfer the spent shuttle from 110 said shuttle-box to said spent-shuttle-platform, said carrier-moving means being arranged to move the carrier to transfer the spent shuttle to said shuttle-support.

11. In a weft-replenishing loom, the combination with a "change" shuttle-box having a shuttle-binder, of a shuttle-engaging device arranged to pass over said shuttle-binder and to act on the rear face of the shuttle, and means arranged to actuate said 120 device when the shuttle-box is inclined toward the rear of the loom to move the shuttle toward the front of the loom.

12. In a weft-replenishing loom, the combination with a "change" shuttle-box having a shuttle-binder, of a shuttle-engaging device mounted upon a pivot arranged under and movable with said shuttle box, the upper portion of said device being arranged to pass over said shuttle-binder, and means 130

- arranged to actuate said device when said shuttle-box is inclined toward the rear of the loom, to move the shuttle toward the front of the loom.
5. 13. In a weft-replenishing loom, the combination with a "change" shuttle-box including a shuttle-binder, of means arranged to interchange a shuttle in said shuttle-box and a spare shuttle, and means arranged to 10 put a full bobbin in the spare shuttle, said shuttle-interchanging means including a shuttle-engaging device arranged to pass over said shuttle-binder and to act on the rear face of the shuttle, and mechanism arranged to 15 actuate said device when said shuttle-box is inclined toward the rear of the loom, to move the shuttle that is in said shuttle box toward the front of the loom.
14. In a weft-replenishing loom, the combination with the "change" shuttle-box, of 20 means arranged to put a full bobbin in a spent shuttle, a shuttle carrier and operating mechanism therefor arranged to transfer shuttles to and fro between said shuttle-box and the first said means, means arranged to 25 clamp a filled shuttle on said carrier, means arranged to transfer a spent shuttle from said shuttle-box to said carrier, and means arranged to clamp the spent shuttle on said carrier.
15. In a weft-replenishing loom, the combination with the "change" shuttle-box, of 30 means arranged to put a full bobbin in a spent shuttle, a shuttle-carrier and operating mechanism therefor arranged to transfer shuttles to and fro between said shuttle-box and the first said means, said carrier having a shuttle-clamping face arranged to 35 engage a filled shuttle and having a shuttle-clamping face arranged to engage a spent shuttle, spring-stressed means carried by said carrier and arranged to coact with the first said face to clamp the filled shuttle, and spring-stressed means carried by said carrier and arranged to coact with the other 40 said face to clamp the spent shuttle.
16. In a weft-replenishing loom, the combination with the "change" shuttle-box, of 45 means arranged to put a full bobbin in a spent shuttle, a shuttle-carrier and operating mechanism therefor arranged to transfer shuttles to and fro between said shuttle-box and the first said means, said carrier having abutments between which a filled shuttle 50 and a spent shuttle may lie, spring-stressed shuttle-clamping means arranged between said abutments to coact with one or more of the latter to clamp a filled shuttle, and spring-stressed shuttle-clamping means carried by the first said clamping means to 55 coact with one or more of said abutments to clamp a spent shuttle.
17. In a weft-replenishing loom, the combination with the "change" shuttle-box, of 60 means arranged to put a full bobbin in a spent shuttle, a shuttle-carrier and operating mechanism therefor arranged to transfer shuttles to and fro between said shuttle-box and the first said means, said carrier having abutments between which a filled shuttle and a spent shuttle may lie, spring-stressed shuttle-clamping means arranged between said abutments to coact with one or more of the latter to clamp a filled shuttle, and spring-stressed shuttle-clamping means carried by the first said clamping means to coact with one or more of said abutments to clamp a spent shuttle.
18. In a weft replenishing loom, the combination with the "change" shuttle-box, of 65 means arranged to put a full bobbin into a spent shuttle, shuttle-clamping means, means arranged to transfer the spent shuttle from said shuttle-box to said shuttle-clamping means, and means arranged to coact with said clamping means to transfer the spent shuttle to the first said means.
19. In a weft-replenishing loom, the combination with the "change" shuttle-box, of 70 means arranged to put a full bobbin into a spent shuttle, a carrier, means arranged to transfer the spent shuttle from the shuttle-box to said carrier, means arranged to clamp the spent shuttle on the carrier, and means arranged to move the carrier to transfer the spent shuttle to the first said means.
20. In a weft-replenishing loom, the combination with the "change" shuttle-box, of 75 means arranged to put a full bobbin into a spent shuttle, shuttle-clamping means, and means arranged to coact with said clamping means to transfer the filled shuttle from the first said means to the shuttle-box.
21. In a weft-replenishing loom, the combination with the "change" shuttle-box, of 80 means arranged to put a full bobbin into a spent shuttle, a carrier arranged to transfer the filled shuttle from said means to the shuttle-box, and clamping means carried by said carrier and arranged to clamp the spent shuttle to transfer the latter to the first said means.
22. In a weft-replenishing loom, the combination with the "change" shuttle-box, of 85 means arranged to put a full bobbin into a spent shuttle, a shuttle-carrier, resilient means carried by said carrier and arranged to transfer the filled shuttle from the first said means to the carrier, and means arranged to coact with said resilient means to clamp the filled shuttle on the carrier, the latter being movable to transfer the shuttle to the shuttle-box.
23. In a weft-replenishing loom, the combination with the "change" shuttle-box, of 90 means arranged to put a full bobbin into a spent shuttle, and mechanism arranged to interchange the spent shuttle in

the shuttle-box and a filled shuttle supported by said shuttle-loading means, said mechanism including a shuttle-carrier having means arranged to clamp the filled shuttle 5 and means arranged to clamp the spent shuttle.

24. In a weft-replenishing loom, the combination with the "change" shuttle-box, of means arranged to put a full bobbin into 10 a spent shuttle, and shuttle-changing mechanism comprising a shuttle-carrier movable back and forth between the shuttle-box and said means to carry the filled shuttle to the shuttle-box and to carry the spent shuttle 15 to said means, and shuttle-clamping means carried by said carrier to hold one of the shuttles thereon.

25. In a weft-replenishing loom, the combination with the "change" shuttle-box, of 20 means arranged to put a full bobbin into a spent shuttle, and mechanism arranged to transfer the spent shuttle from the shuttle-box to said means, said mechanism including shuttle-clamping means arranged to 25 clamp the spent shuttle during transit.

26. In a weft-replenishing loom, the combination with the "change" shuttle-box, of 30 means arranged to put a full bobbin into a spent shuttle, and shuttle-changing mechanism comprising a carrier arranged to transfer a filled shuttle to said shuttle-box and to transfer the spent shuttle to said means, and shuttle-clamping means arranged to clamp the filled shuttle during transit.

35 27. In a weft-replenishing loom, the combination with the "change" shuttle-box, of means arranged to put a full bobbin into a spent shuttle, and shuttle-changing mechanism arranged to transfer a filled shuttle from said means to the shuttle-box and to transfer the spent shuttle from the shuttle-box to said means, said mechanism comprising clamping means arranged to clamp the filled shuttle during transit.

40 28. In a weft-replenishing loom, the combination with the "change" shuttle-box, of means arranged to put a full bobbin into a spent shuttle, means arranged to carry the filled shuttle from the first said means to

said shuttle-box, and spring-stressed shuttle-clamping means carried by said carrying means and arranged to hold a spent shuttle. 50

29. In a weft-replenishing loom, the combination with the "change" shuttle-box, of means arranged to put a full bobbin into a 55 spent shuttle, a shuttle-carrier and operating means therefor arranged to carry a spent shuttle to the first said means, means arranged to transfer the spent shuttle from said shuttle-box to said carrier, and means 60 arranged to clamp the spent shuttle on said carrier.

30. In a weft-replenishing loom, the combination with the "change" shuttle-box, of means arranged to put a full bobbin into a 65 spent shuttle, a shuttle-carrier, shuttle-clamping means carried by said carrier and arranged to hold a shuttle thereon, said shuttle-clamping means including a spring-stressed shuttle-clamping element, means 70 arranged to transfer a spent shuttle from said shuttle-box to potential clamping position relatively to said shuttle-clamping means, means arranged to displace said spring-stressed element to open said shuttle-clamping means for the reception of the spent shuttle, and means arranged to move said carrier to transfer the spent shuttle to the first said means. 75

31. In a weft-replenishing loom, the combination with the "change" shuttle-box, of 80 means arranged to put a full bobbin into a spent shuttle, means arranged to carry the filled shuttle from the first said means to said shuttle-box, and shuttle-clamping 85 means carried by said carrying means to hold the shuttle thereon.

32. In a weft-replenishing loom, the combination with the "change" shuttle-box, of means arranged to put a full bobbin into a 90 spent shuttle, a shuttle-carrier and operating means therefor arranged to carry a shuttle to and from the first said means, and shuttle-clamping means carried by said carrier to hold the shuttle thereon. 95

In testimony whereof I have affixed my signature.

LEONARD AITKEN.
